UNITED STATES PATENT OFFICE.

ALONZO L. BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

REFINING APPARATUS.

Application filed August 18, 1922. Serial No. 582,788.

To all whom it may concern:

Be it known that I, ALONZO L. BAUSMAN, citizen of the United States, residing at Springfield, in the county of Hampden and State of Massachusetts, have invented new and useful Improvements in Refining Apparatus, of which the following is a specification.

This invention relates to refining apparatus and, more particularly, to apparatus adapted for refining or conditioning chocolate and the like by rubbing action.

An example of the type of apparatus, with which this invention is concerned, is the so-called "conge" or "Swiss rubbing machine" and it consists essentially of a heavy roll, usually of granite, reciprocable upon a bed, also usually of granite, which bed forms the base of a tank containing the chocolate or other material to be refined. The conge has long been used by chocolate manufacturers and is well-known in the art.

In refining apparatus of this class, it has been found by experience that there is a definite limit in the size to which the tank may be built. Beyond this limit, an increase in size reduces the efficiency of the refining action. Therefore, it is not practical to provide for increased capacity by employing tanks of extra large size. Hence, instead of one large tank, it is preferable to use a number of smaller tanks in order to retain the highest efficiency in refining the chocolate. In large factories, where such refining machines are used in great numbers, this limitation of size now necessitates the occupation of a large area of valuable floor space to accommodate the many small tanks.

Bearing in mind the necessity for the use of a number of units, efforts have been made toward grouping a series of individual conges into a single machine which will afford a maximum aggregate capacity with a minimum of floor space and one example of such an arrangement is shown in United States Letters Patent No. 1,176,722, granted March 21, 1916 on an invention of Frank H. Page in chocolate refining apparatus. The apparatus disclosed in this patent is characterized by a "double deck" arrange-

ment of conges, there being two series of tanks arranged at different levels and two sets of driving mechanism and supporting frames therefor. This apparatus, while attaining its object and affording the best arrangement of units from the point of view of economy in floor space, has not in many instances found favor with the trade because of the inconvenience in filling and emptying the tanks of the upper level at the start and end of the refining operation and in inspecting the material in these tanks during the refining operation. Moreover, the apparatus, as described in said patent, necessitates a duplication of driving mechanism as well as a duplication of tanks and therefore is more expensive to manufacture and is also open to the disadvantage of increased friction losses due to the increased number of parts in the driving mechanism.

In all the various grouping arrangements heretofore used or proposed for conges, a waste space (in the sense that it cannot be used for chocolate) is provided between each pair of adjacent and opposed tanks, such space being utilized for the driving mechanism which reciprocates the rubbing rolls. The proportion of the floor space occupied by such driving mechanism to the total floor space occupied by the entire machine is from twenty five to thirty per cent in the usual four unit machine. Up to the present time, so far as I am aware, it has not been considered possible to eliminate this waste space on account of the difficulty in adequately supporting the driving mechanism, which is heavy and cumbersome, in proper relation to the conge tanks or, in other words, it has been deemed a necessary evil that the driving mechanism should occupy floor space and prevent the utilization of such floor space for the reception of chocolate or other material to be refined.

According to this invention, each conge tank is extended a substantial distance beyond the tank opening to provide a shelf like portion and the driving mechanism is superposed upon and supported from these shelf like portions of adjacent conge tanks.

According to another feature of the in-

vention, the conge tanks, which are arranged in one or more pairs, preferably have the tanks of each pair arranged with their ends in abutment, or substantially so, thereby 5 eliminating any waste area between the tanks and providing for the maximum economy in utilizing the principles of this invention. When more than one pair of conge tanks are used the sidewalls of the tanks 10 of one pair are disposed as closely as possible to the corresponding side walls of the adjacent pair so that practically all floor space occupied by the machine is usefully occupied by tanks for containing the material 15 to be refined.

According to a further feature of the invention, there is provided in each conge tank, in addition to the usual rubbing roll, one or more scrapers, preferably of the 20 swinging type, which are located in the end portions of the tank and function to periodically scrape the chocolate from such end portions back into the central portion of the tank or into a location where it is again 25 presented to the action of the rubbing roll. The utility of these scrapers, located as described, will best be appreciated when it is understood that the stroke of the rubbing roll has to be substantially commensurate 30 with the length of the tank opening and, therefore, the lengthening out of the tank, as above described, results in spaces which would otherwise be dead spaces except for the scrapers. That is, although the capacity 35 of the tank is increased by lengthening it the efficiency of the refining action would be somewhat impaired unless means are provided to insure that the chocolate in the end portions of the tank is presented to the action 40 of the rubbing roll.

Any one or more of the inventive features may be employed as desired but the best results are manifestly obtained by the use of all conjointly.

Other objects and advantages will appear in the following description and in the illustrative embodiment of the invention in the accompanying drawings, in which:

Fig. 1 is a front elevational view, partly 50 in section, of a refining apparatus embodying the invention;

Fig. 2 is a fragmentary end elevational view thereof;

Fig. 3 is a plane view of the apparatus; 55 and

Fig. 4 is a fragmentary cross-sectional view of one of the conge tanks showing the rubbing roll and the fork by which it is reciprocated.

Referring to these drawings; the apparatus 60 preferably includes four units A, B, C and D, which are arranged in two opposed pairs,—the units A and B constituting one pair and the units C and D the other pair. Both pairs of units are arranged in parallel

relation,—one pair being located directly behind the other. All the units are located on the same level and are suitably supported, as from a floor. The two units of each pair are mounted in line with one another and 70 preferably abut, or substantially abut, end to end as shown. While one pair of units alone may be used, the same driving mechanism is adequate for two pairs and accordingly the two pairs are generally desired, 75 particularly as a better balanced and smoother acting mechanism is obtained, as will later appear. When two pairs of units are employed the second pair is preferably mounted side to side in abutting relation 80 with the other pair.

All of the units referred to, are similar and a description of one will suffice for all. The unit B consists of a structure supported by legs 5 and affording a tank 6 for the reception of the material to be refined. The bottom of the tank is usually slightly curved longitudinally and merges into end walls of pronounced and substantially semi-circular curvature. In the bottom wall of the tank, 90 a bed 7 of suitable material, such as stone, is generally provided and upon and along this bed a roll 8 usually also of stone, is reciprocable. Roll 8 is reciprocated by means of a fork 9, the central upper 95 portion of which extends upwardly through an opening 10 in the top of the tank for connection to reciprocable mechanism, to be described. The opening 10 is made substantially equal in width to the tank to 100 permit insertion of roll 8 and its length defines the limits of the stroke of roll 8. This opening, which is used for filling the tank with the material to be refined, is normally enclosed by a cover 11, mounted in 105 any suitable fashion so as to be conveniently removable. The refined material may be drained from the tank through a side outlet normally closed by a vertically sliding gate 13, (shown on unit A) which is liftable by 110 a handle 14 in an obvious manner to open the outlet and permit the material to flow therethrough over a sloping trough 15 into a suitable container.

As distinguished from an ordinary conge 115 unit, the present one has been extended a substantial distance beyond the ends of opening 10 which increases the capacity of the tank and also allows a flat shelf-like portion 17 to be provided on one end. Such portion abuts and aligns with a similar portion on the unit B and the two provide a base of adequate area to receive and support an upstanding side frame 18. Similar portions are provided on the other pair of units 120 to support a second and similar but laterally spaced side frame. These two side frames support the driving mechanism, to be described, and it is to be noted that the frames are applied to the tops of the tanks and are 125 130

superposed thereon as distinguished from being supported between them as has heretofore been customary. The present driving mechanism requires no exclusive use of floor space, as formerly, but on the contrary the floor space, which it occupies, is also used for tank space for the reception of material to be refined and is thus used usefully and economically.

10 The driving mechanism includes a crank-shaft 20 which is rotatably mounted near its ends in the side frames 18 and extends beyond each of the latter to carry cranks 21 and 22, one fixed to each end thereof. Fixed 15 on shaft 20 intermediate the frames 18 is a gear 23 which is driven by a pinion 24 fixed on a shaft 25,—the latter being the main power shaft and being driven in any suitable manner, as by belt connection to the 20 tight and loose pulleys 26. The forks 9 of units A and B are rigidly connected to a common rod 26 and one of the forks 9 has an arm 27 which extends vertically upwards through a longitudinal slot 28 provided in 25 hood 11 and is pivotally connected to one end of a link 29, the other end of which is connected to crank 21. The forks 9 of units C and D are similarly connected and driven from crank 22 which is mounted on shaft 20 30 at right angles to crank 21, the better to balance the operating mechanism, eliminate dead center difficulties and insure a smoother action in operation.

The scrapers, heretofore alluded to, are 35 provided in the semi-cylindrical end portions of each conge tank and, as shown, two similar scrapers 30 and 31 are provided in each such end portion. Each scraper consists of a cross bar, herein shown of substantially 40 triangular cross section, which is approximately equal in length to the width of tank 6. Each scraper is supported by radial arms 32 from a shaft 33 which passes through the conge tank and is journaled in the side 45 walls thereof, substantially coincidental with the axis of curvature of the adjacent curved end portion of tank 6. The scrapers 30 and 31 are fixed to shaft 33 in right angular relation and this shaft is oscillated, by 50 mechanism to be described, through an arc of ninety degrees so that the scraper 30 traverses the upper half of the semi-circular end surface of tank 6 and the scraper 31 traverses the lower half. The two scrapers working 55 in conjunction to traverse the entire end wall surface are not necessarily essential for all purposes and their work might obviously be accomplished by a greater or less number of scrapers operating through lesser or 60 greater ranges of travel.

All of the scraper shafts are oscillated from a common driving means and all the driving mechanism is located in a comparatively narrow longitudinal space between the 65 two pairs of units as is best shown in Fig. 2.

This space is covered by flanges 35, one on each unit, which flanges abut as shown in Fig. 3 to form a complete covering for the space in which the scraper operating mechanism is located and thereby prevent any 70 chocolate, which might be spilled or slopped over from the tanks, from falling into such space. Each shaft 30 extends into the latter sufficiently to carry a crank 36 and each crank of the front pair of units will lie opposite a crank of the rear pair of units so that there are four pairs of cranks, and the free ends of the cranks of each pair lie in close adjacency and are disposed in the same angular relation on their respective cranks. 75 Accordingly, the cranks of each pair may be pivotally connected to a common member, such as 37, and all these members are fixed to a common reciprocable operating rod 38. The latter has fixed thereto a depending arm 39 which is connected by a link 40 to a crank arm 41. The latter is fixed to and rotated by a stub shaft 42, suitably supported in one of the conge units, and shaft 42 is driven through the medium of a chain 43 and sprockets 44 from the crankshaft 20, formerly described.

In addition to the scrapers just described, I prefer to provide other scrapers which traverse the longitudinal spaces between the 95 ends of rolls 8 and the adjacent side walls of tank 6. Necessarily the ends of rolls 8 cannot meet the sides of the tank on account of the forks 9 and I extend one arm of each fork downwardly, as indicated at 46, into close proximity to the bed 7 for this purpose.

The operation of the machine is the same as any conge, except for the scrapers described, and will be readily apparent. The scrapers 30 and 31 preferably assume the positions shown in the left hand end of unit B when roll 8 is at the end of its travel toward them and move from this position downwardly as roll 8 moves away from them, assuming the positions shown in the right hand end of unit B at the end of the last named stroke of travel.

The refining apparatus disclosed is characterized by a most economical utilization of floor space and the arrangement is such that there is very little of the occupied floor space but what is used for tank space. By lengthening out the tanks and providing the scrapers beyond the tanks, I am enabled to increase the capacity of each conge unit, by more than double that heretofore thought feasible, without materially affecting the efficiency of the refining operation. For example, the conge tanks shown have an aggregate capacity of 4000 pounds of chocolate while those previously used had an aggregate capacity of 1600 pounds in a four unit machine or 3200 pounds in an eight unit double deck machine and yet the floor space 130

occupied by the present machine is appreciably less than that occupied by either of the two last named machines.

The invention has been disclosed herein, 5 in an embodiment at present preferred for illustrative purposes but the scope of the invention is defined by the appended claims rather than by the foregoing description.

What I claim is:—

- 10 1. Refining apparatus, comprising, a pair of conge tanks mounted end to end in substantially abutting relation, a frame superimposed upon the end portions of adjacent tanks and located entirely above the latter, a driving shaft rotatably mounted in said frame, a reciprocable rubbing roll in each tank, and connections between each roll and said shaft to reciprocate the rolls.
- 20 2. Refining apparatus, comprising, a group consisting of pairs of conge units, the units of each pair being mounted end to end in substantially abutting relation and the units of one pair being disposed side to side in substantially abutting relation with the units of the other pair, a reciprocable rubbing roll in each tank, a driving shaft common to all the tanks, connections between said shaft and each roll for reciprocating the latter, and supporting means for said shaft superposed substantially centrally upon the top walls of said group of tanks and located entirely above the latter.
- 30 3. Refining apparatus, comprising, a pair of conge tanks mounted end to end in substantially abutting relation and each having an opening in its top wall of less length than that of the tank, a rubbing roll reciprocable in each tank, an operating member for each roll extending out of the tank through said opening, a frame supported by the top walls of the tanks between said openings and located entirely above the latter, a driving shaft mounted in said frame, and connections between said shaft and each of said operating members.
- 40 4. Refining apparatus, comprising, a pair of conge tanks mounted end to end in substantially abutting relation and each having an opening in its top wall of less length than that of the tank, a rubbing roll reciprocable in each tank, an operating member for each roll extending out of the tank through said opening, means rigidly connecting said operating members, a frame supported by the top walls of the tanks between said openings and located entirely above the latter, a driving shaft mounted in said frame, and connections between said shaft and said means.
- 50 5. Refining apparatus, comprising, two conge tanks arranged with their longitudinal axes in alinement, openings provided in the top wall of each tank so disposed as to leave at one end of each a shelf forming portion, beneath which a portion of the tank extends, 60 a frame supported partly on the shelf form-

ing portion of one tank and partly by the corresponding portion of the other tank and located entirely above the tanks, a roll reciprocable in each tank, driving mechanism mounted in said frame, and connecting means between such mechanism and each roll to reciprocate the latter.

6. Refining apparatus, comprising, a conge tank, a roll movable back and forth therein along the base, a fork shaped member for moving the roll having a depending arm disposed between each end face of the roll and an adjacent side wall of the tank, and scraping means carried by each arm depending into close proximity to the base.

7. Refining apparatus, comprising, a conge tank having a bed and a portion extending beyond the bed, a roll movable back and forth over the bed and having a stroke less than that of the tank so that it cannot traverse said portion, and an oscillatory member movable back and forth over said portion simultaneously with the reciprocation of said roll, said member operable to move away from said bed toward the outer extremity of said portion as the roll approaches thereto and to move back toward the bed as the roll recedes to scrape back the material thrown onto the walls of said portion by the approaching movement of said roll.

8. Refining apparatus, comprising, a conge tank having a bed and two oppositely curved end walls disposed one at each end of the bed, a roll reciprocable back and forth over said bed, and oscillatory members mounted for movement in paths entirely out of the path of said roll and associated one with each end wall and arranged to traverse the same, each of said members arranged to move outwardly along its end wall as the roll approaches the same and to move back again as the roll recedes to scrape back the material thrown against said wall by the roll in its movement of approach thereto.

9. Refining apparatus, comprising, a conge tank having a bed terminating with two oppositely located curved end walls, a roll reciprocable back and forth along the bed, two members mounted in right angular relation to swing back and forth about the axis of curvature of each end wall, and means for moving said roll and members.

10. Refining apparatus, comprising, a conge tank having a bed terminating with two oppositely located curved end walls, a roll reciprocable back and forth along the bed, two members mounted in right angular relation to swing back and forth about the axis of curvature of each end wall, the members at one end of the tank being disposed at right angles to the corresponding members at the other end of the tank.

11. Refining apparatus, comprising, two pairs of conge tanks, the tanks of each pair

- being longitudinally alined in end to end and abutting relation and the tanks of one pair being mounted in side by side and slightly spaced relation with the tanks of each shaft and located in said space, a connecting rod to which all said cranks are connected, and means for reciprocating said rod. 25
- 5 the other pair, a roll reciprocable in each tank, an oscillatory shaft mounted at each end of each tank beyond the travel of said roll, scraping means carried by each shaft, the shafts of each tank projecting into the 30 space between the pairs of tanks, and mechanism in said space for connecting said shafts and oscillating them. 35
12. Refining apparatus, comprising, two pairs of conge tanks, the tanks of each pair being longitudinally alined in end to end relation and the tanks of one pair being mounted in side by side and slightly spaced relation with the tanks of the other pair, a roll reciprocable in each tank, an oscillatory shaft mounted at each end of each tank beyond the travel of said roll, scraping means carried by each shaft, the shafts of each tank projecting into the space 40 between the pairs of tanks, and mechanism in said space for connecting said shafts and oscillating them and means provided on the conge tanks to overlie said mechanism and cover said space. 45
- 15
- 20

In testimony whereof I have affixed my signature.

ALONZO L. BAUSMAN.
